UNITED STATES PATENT OFFICE

GEOERGE F. WIKLE, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS

PLYING MACHINE

Application filed September 4, 1926. Serial No. 133,609.

My invention relates to a device for plying up strips of material such as rubberized fabric or rubber, or a combination of the two.

It is an object of my invention to provide a machine for this purpose which, while operating at a relatively high speed will accurately position the strips in desired relation and without distortion. A further object is to provide a device for this purpose such that the various strips of material make minimum contact with the machine parts, to the end that the tension may be controlled and a uniform stretch obtained. Other and further objects will be apparent from the following specification and claims.

In the accompanying drawings which illustrate one embodiment of my invention

Figure 1 is a front elevation of the machine,

Fig. 1a is a detail view on an enlarged scale showing the drive for the plying rolls,

Figure 2 is an end elevation,

Figure 3 is a front elevation on a larger scale of one of the plying units, parts being broken away,

Figure 4 is a plan view, on a similar scale, of one of the plying units,

Figure 5 is a perspective view of one of the guide units,

Figure 6 is a detail of one of the material supply racks, looking from the right in Figure 2,

Figure 7 is a perspective view of the means for applying a strip in reversed order,

Figure 8 is a detail of the switch box and,

Figure 9 is a diagrammatic perspective view showing the manner in which the material is plied.

Referring to the drawings 1 designates a table along the forward edge of which are secured a plurality of uprights 2 carrying a transverse member 3 on which are mounted a plurality of plying units 4 later described.

A plurality of racks 6, one for each plying unit, are mounted along the rear edge of the table 1. As best shown in Figures 2 and 6 these racks each comprise an upright 7 revolvably secured to the table, as indicated at 8 and provided at its upper end with a slotted

stud 9 journaled in a flat bar 11 projecting rearwardly from bar 3. The rack is releasably held against rotation by a locking member 12 pivoted at 13 to bar 11. One arm of the locking member engages the slot in stud 9, the other arm being connected by rod 14 to a handle 15 by which the lock may be released. Pairs of spindles project from opposite sides of upright 7. The lower spindles 16 are adapted to hold a roll of rubber or rubberized fabric 17 wound up in a suitable liner 18 while the upper spindles 20 are adapted to receive the liner as the material is drawn therefrom. As best shown in Figure 6 the material, as it is unwound passes over the liner roll on the upper spindle thus driving the latter. While one side of the rack 21 is in use the other may be loaded. When the first roll is exhausted the operator releases lock 12, turns rack 6 through 180° to bring the new roll of material into position and splices the leading end of the fresh roll of material to the previous strip.

The plying units 4 with an exception later described, are exactly similar and a description of one will serve for all. As best shown in Figures 3 and 4 these units comprise a pair of driven rolls 25 and 26, journaled in a plate 27 secured to bar 3. Rolls 25 and 26 are provided, adjacent plate 27, with pulleys 30 and 31 respectively which are driven by belt 32 as later described. Adjacent to rolls 25 and 26 are guides 33.

As best shown in Figure 5 these guides comprise three rods 39, 40 and 41 secured to plate 27, their free ends being maintained in proper position by a head 42. Rod 39 carries a freely rotatable cylindrical roller 34 over which the strips pass between adjustable guide elements 35 and 36 adapted to be secured in adjusted position by clamps 37 and 38 engaging rods 40 and 41. A roll 44 is adjustably mounted to ride freely on roll 25. Roll 44 which is designed to be changed, as occasion may require, to suit varying widths of material is freely rotatable on a stub shaft 45 carried by an arm 46 pivoted on bar 47 the latter secured as at 48 to plate 27.

The compound strip indicated in Figure 3 by dotted line 50 comes to the plying units 100

over guide 33 adjacent roll 26, passes under roll 26 and over roll 25 against which it is maintained in position by roll 44. The strip 51 to be added by the particular plying unit 5 passes from rack 6 (see Figure 2) beneath a milled roll 52 secured on the main drive shaft 53. From roll 52 strip 51 passes around a freely rotatable guide roll 54 adjustably mounted at 55 (Figures 3 and 4) on an arm 10 56 secured to an upright 2. After leaving roll 54 the web 51 is turned through an angle of 90°, passing upwardly to guide 33 adjacent roll 25, thence around roll 25 and beneath strip 50 to which it adheres.

15 The first strip fed to the machine enters the machine at the right hand end as shown in Figure 1, passes through a guide 33 such as has been described, and over a single roll 57 to the first plying unit. Between each plying unit is positioned an adjustable guide 58 mounted on a rod 59 secured to bar 3. As the compound strip passes each successive plying unit a strip is added to the under surface, the successive strips being lettered "a" 20 to "e" inclusive in Figure 9 which diagrammatically shows the operation as a whole.

25 It is sometimes desirable to add a strip "f" in reverse order, that is on top of rather than beneath the previous strips, so as to overlap the edges of one or more of the previously 30 plied strips, and I provide means for accomplishing this in connection with the last plying unit (the left hand unit as viewed in Figure 1). This means is best shown in Figure 35 7, and in addition to the mechanism of the plying unit just described, comprises a cylindrical guide roller 60 supported from a block 61 adjustably secured to an extension of bar 47. A similar guide roller 62 is supported 40 from a block 63 also adjustably mounted on bar 47. Directly beneath roller 62 is a guide member 64 secured to block 63. A loop shaped guide 65 is secured to the guide unit 33 adjacent roll 26. As in the operation previously described the compound strip passes over guide 33, then beneath roll 26 and over roll 25. The strip "f" to be applied to the top of the compound web passes upwardly from its roll 54, untwisted, through loop 65 45 over rollers 60 and 62, is twisted through 90° between roller 62 and guide 64 and from the latter passes to its position on top of the compound web.

50 It is to be noted that the rolls 52, 25 and 26 move the strips forward by surface contact only, the rolls 44 exerting only sufficient pressure to maintain the strips in relative position and assure adhesion of the strips if the stock is dry, but under ordinary circumstances may be omitted. It is desirable, both to maintain the strips in uniform contact with the rolls 52, 25 and 26 and to impart a slight stretch to the strips, that a certain amount of tension be applied to the latter 55 and this is accomplished by driving rolls 25

and 26 of the last plying unit at a slightly increased speed, as by making the pulleys of these rolls slightly smaller than those by which the preceding rolls are driven, as shown at 30' and 31' in Fig. 1a. This applied tension is substantially uniformly distributed back through the various plying units since while it acts with greatest force at the units immediately preceding that at which it is applied the compound web with the addition of each strip becomes correspondingly stiffer with the result that while the applied tension at the farthest unit is less it produces substantially the same effect.

55 The completed compound strip passes from the last plying unit over a roll 70 and down-dowly to a wind-up mechanism. As shown in Figure 1 roll 70 is carried by a block 68 threaded on a screw 69 provided with a crank 81 by which the position of roll 70 may be adjusted in an obvious manner.

60 The wind-up mechanism is best shown in Figure 2. A roll of suitable liner material 71 is mounted on a reel 72 carried by a bracket 73 secured to the main frame. From reel 72 the liner passes over a suitable guide 74 extending from a bracket 75 secured to the frame. Guide 74 forms the pivot for a bell crank lever 76, one arm of which carries a roll 77, the other arm being connected by spring 78' to the frame. Spring 78' acts to press roll 77 against a roll 78 mounted on the end of main drive shaft 53. From guide 74 the liner passes around roll 77 thence around roll 78 to a wind-up roll 79 carried by a spindle 80 journaled in the main frame. The compound web passes from roll 70 through guides 82 and around roll 83 to the top of roll 78 where it meets the liner. Guides 82 and roll 83 are adjustably secured to a bracket 84 100 suitably secured to table 1.

65 Power for driving the machine is furnished from a motor 90 secured to the underside of the table 1, see Figures 1 and 2. The shaft of the motor carries a sprocket 91 connected by a sprocket chain 92 to sprocket 93 on the main drive shaft 53. Belt 32 which drives the plying rolls passes around a pulley 94 positioned centrally of shaft 53, passing from pulley 94 about idle pulleys 95 to the plying roll pulleys, as will be clear from Figure 1. The use of a belt for driving rolls 25 and 26 70 renders the drive of each unit substantially independent as the belt may slip on the pulleys if the resistance varies. Wind-up spindle 80 is driven by a sprocket chain 96 passing around sprockets 97 and 98 carried respectively by the spindle 80 and main drive shaft 53, sprocket 97 being connected to spindle 80 through a slip clutch indicated at 89.

75 The machine is conveniently controlled by a switch box 100 (see Figures 1, 2 and 8) provided with stop and start buttons 101 and 100

102 and a reduced speed button 103. These buttons are operated from a bar 104 running the length of the machine and slidably and rotatably supported in brackets 105 secured to table 1. Bar 104 carries arms 106 and 107 adapted to respectively operate buttons 101 and 102 upon the reciprocation of bar 104. A third arm 108 secured to bar 104 is adapted to operate reduced speed button 103 upon rocking of bar 104 in an obvious manner. The electrical connections between switch box 100 and motor 90 are conventional and for the sake of clearness are omitted.

I claim:

1. A device of the character described comprising a plurality of spaced pairs of driven rolls, the rolls of each pair being spaced from each other in the direction of strip travel and positioned to make arcuate contact with opposite sides of a moving strip of material and means associated with one roll of each pair of feed an additional strip of material between that roll and the first mentioned strip to progressively form a multi-ply strip.

2. A device of the character described comprising a plurality of spaced pairs of driven rolls, the rolls of each pair being spaced from each other in the direction of strip travel and positioned to make arcuate contact with opposite sides of a moving strip of material, means associated with one roll of each pair to feed an additional strip of material between that roll and the first mentioned strip to form a multi-ply strip, and yielding rolls adapted to maintain said strips in relative position as they pass over said driven rolls.

3. A device of the character described comprising a plurality of spaced pairs of driven rolls, the rolls of each pair being spaced from each other in the direction of strip travel and positioned to make arcuate contact with opposite sides of a moving strip of material, means associated with one roll of each pair to feed an additional strip of material between that roll and the first mentioned strip to form a multi-ply strip and means to drive the last pair of rolls at a slightly greater speed than the preceding rolls to apply tension to the multi-ply strip as it is being formed.

4. A device of the character described comprising a plurality of spaced pairs of driven rolls, the rolls of each pair being spaced from each other in the direction of strip travel and positioned to make arcuate contact with opposite sides of a moving strip of material, adjustable means associated with one roll of each pair to feed an additional strip of material between that roll and the first mentioned strip, in predetermined relation with the latter, to form a multi-ply strip and means to apply a predetermined degree of tension to the multi-ply strip as it is being formed.

5. A device of the character described comprising a plurality of spaced pairs of non-engaging rolls adapted to freely advance a strip of material through arcuate contact therewith, means associated with each pair of said rolls to bring an additional strip into adhering contact with the advancing strip and means to apply a substantially uniform tension to the so formed multi-ply strip as it is being formed.

6. A device for plying two strips of material in predetermined relation comprising a driven roll beneath which a strip of material is adapted to pass, a second driven roll spaced from said first roll in the direction of strip travel over which said strip is adapted to pass, said rolls making arcuate contact with said strip, means to guide a second strip of material over said second roll and beneath said first strip and a third roll mounted to ride freely on said strips as they pass over the second named roll.

7. A device, for successively plying a plurality of strips of material together to form a compound strip, comprising a plurality of parallel, independently driven rolls arranged in spaced pairs, the rolls of each pair being spaced from each other in the direction of the travel of the compound strip and positioned to make arcuate contact with opposite sides of the latter, and means associated with each pair of rolls to feed a strip of material between the partially formed compound strip and one roll of the pair.

8. A device, for successively plying a plurality of strips of material together to form a compound strip, comprising a plurality of parallel, independently driven rolls arranged in spaced pairs, the rolls of each pair being spaced from each other in the direction of the travel of the compound strip and positioned to make arcuate contact with opposite sides of the latter, means associated with each pair of rolls to feed a strip of material between the partially formed compound strip and one roll of the pair, and means to apply sufficient tension to the compound strip to maintain the strip, as it is formed, in driven relation with the rolls.

9. A device, for plying a plurality of strips together to form a compound strip, comprising a pair of parallel, driven rolls spaced from each other in the direction of strip travel and positioned to make arcuate contact with opposite sides of a strip of material, and means to feed a second strip of material between one of said rolls and the first mentioned strip.

10. A device, for plying a plurality of strips together to form a compound strip, comprising a pair of parallel, driven rolls spaced from each other in the direction of strip travel and positioned to make arcuate contact with opposite sides of a strip of material, means to feed a second strip of ma-

130

terial between one of said rolls and the first mentioned strip, and means to apply sufficient tension to the compound strip to maintain the strip, as it is formed, in driven relation with the rolls.

5 In testimony whereof I have signed my name to the above specification.

GEORGE F. WIKLE.

CERTIFICATE OF CORRECTION.

Patent No. 1,795,915.

Granted March 10, 1931, to

GEORGE F. WIKLE.

It is hereby certified that error appears in the printed specification of the above numbered patent requiring correction as follows: Page 2, lines 81 and 82, for the word "down-downly" read downwardly; page 3, line 22, claim 1, for "of" first occurrence read to; and that the said Letters Patent should be read with these corrections therein that the same may conform to the record of the case in the Patent Office.

Signed and sealed this 21st day of April, A. D. 1931.

(Seal)

**M. J. Moore,
Acting Commissioner of Patents.**
